UNITED STATES PATENT OFFICE.

JOHN D. KARLE, OF ROSELLE PARK, NEW JERSEY, ASSIGNOR TO THE SINGER MANUFACTURING COMPANY, A CORPORATION OF NEW JERSEY.

SEWING-MACHINE SLACK-THREAD CONTROLLER.

1,209,972.

Specification of Letters Patent. Patented Dec. 26, 1916.

Application filed March 30, 1915. Serial No. 17,982.

To all whom it may concern:

Be it known that I, JOHN D. KARLE, a citizen of the United States, residing at Roselle Park, in the county of Union and State of New Jersey, have invented certain new and useful Improvements in Sewing-Machine Slack-Thread Controllers, of which the following is a specification, reference being had therein to the accompanying drawings.

- 10 This invention has for its object to provide a simple, effective and inexpensively constructed slack-thread controlling device for use in connection with a thread-tension device.
- 15 According to the present improvement, in its preferred embodiment, the tension-stud is secured for circular adjustment in a bushing riveted within a suitable aperture of a sheet-metal face-plate which is formed with 20 concentric apertures to receive prongs or rivets at one end of a sheet-metal casing surrounding said bushing and preferably provided with a lateral loop affording a socket to receive the thread-guard pin over 25 which the thread is led from between the tension-disks sustained by the stud. The tension-stud is surrounded by a spring having one end attached thereto and provided at the opposite end with a lateral thread- 30 arm resting normally against the shoulder of a tubular stop-member which is fitted to the cylindrical inner wall of the casing to which it is secured by a clamp-screw in circularly adjustable relation.
- 35 In the accompanying drawings, Figure 1 is a sectional plan of a sewing machine face-plate provided with a tension device and a slack-thread controller embodying the present improvements. Fig. 2 is a front end 40 view and Fig. 3 a rear end view of the sheet-metal casing and the parts contained therein. Figs. 4 and 5 are perspective views, respectively, of the sheet-metal casing with the thread-guard pin sustained thereby and 45 the tubular stop-member. Fig. 6 is a perspective view of one end portion of the controller-spring. Fig. 7 is a perspective view of the tension-stud.

The face-plate 1 is formed of sheet-metal 50 of the usual arched shape. It is formed at one side of its arched portion with an aperture entered by the central boss or stud 2 of the bushing 3 which is provided with a central bearing aperture 4. This aperture 5 receives the reduced inner end portion 5 of

the tension-stud having the screw-threaded and split outer portion 6 and the intermediate enlargement 7. The part 7 of the tension-stud has adjacent the portion 5 a boss 8 whose extremity affords a spacing shoulder 60 adapted to rest upon the face of the bushing 3, the parts 7 and 8 having therein a longitudinal groove 9.

The outer portion of the tension-stud has applied thereto the tension-disks 10 of well known construction, one of which has superposed thereon the arched washer 11 apertured to fit the exterior of the stud and provided with a cross-bar 12 passing through the slit of the portion 6 of the stud. Between said washer and the nut 13 applied to the threaded part of the outer end portion 6 is interposed the usual tension-spring 14.

Surrounding the bushing 3 and the body 75 portion of the tension-stud is the cylindrical casing composed of a single strip of sheet-metal which is formed into a hollow cylinder 15 having at one side the integral loop 16 to afford a substantially cylindrical 80 socket for the shank of the thread-guard pin. The opposite ends of the sheet-metal blank preferably terminate in a slit 17 at a side of the body of the casing remote from the socket 16, the part 15 being formed at 85 one end with a circular series of prongs 18 which enter a similar series of apertures in the face-plate concentric with the aperture 4, in which apertures they are secured by upsetting or riveting.

90 The socket 16 is entered by the straight portion of the thread-guard pin 19 having at its outer end the lateral segmental guard-arm 20 extending beyond the tension disks and partially embracing the spring 14 in 95 a well known manner. The pin 19 may be secured in its socket by the employment of a fusible bond, as in the use of a drop of solder to unite the parts or by the fusion of the parts to be united by the process of, 100 electric welding, which is deemed preferable. In either case, it is desirable to cause the opposite walls of the socket to firmly adhere to the pin so as to unite them together and secure rigidity of the casing on the side 105 thereof at which the socket is formed.

Fitted to the inner wall of the casing 15 is the tubular stop-member 21 formed of a sheet-metal blank with its ends abutted to form the slit 22 adjacent which is formed 110

in its outer end the notch 23 to afford a stop-shoulder 24. The member 21 is provided intermediate its ends with the threaded aperture 25 entered by the shank of the clamp-screw 26 passing through a segmental slot 27 in the casing 15 and adapted to secure the stop-member to the casing in circularly adjusted position to determine the location of the stop-shoulder 24. Sur-
10 rounding the enlarged portion 7 of the tension-stud is the controller spring 28 having one end 29 bent at right angles with the adjacent coil substantially parallel with its axis to enter the groove 9 above the boss 8, as represented in Fig. 1; the opposite end 15 of said spring having a laterally extending arm 30 normally resting against the stop-shoulder 24 and provided with a thread-engaging loop 31. The boss 8 serves to pro-
20 vide an annular space for the end portion of the spring 28 adjacent the part 29 to prevent the crushing of the end portion of the spring and permit freedom for its adjustment by turning the tension-stud.

25 The bushing 3 is formed with a radial threaded aperture to receive the set-screw 32 passing through a round clearance aperture 33 of the casing and an elongated clearance aperture 34 of the relatively ad-
30 justable stop-member 21 and bearing upon the reduced portion 5 of the tension-stud. By loosening the set-screw 32, the tension-
35 stud may be turned to wind up or unwind the controller-spring 28 and thereby vary the stress of the controller spring-arm 30 upon the thread leading from between the tension-disks without disturbing the adjustment of the stop-shoulder 24; while the stop-
40 member 21 may be circularly adjusted relatively to the tension-stud and the surrounding casing by temporarily loosening the clamp-screw 26.

As represented in Fig. 1, the tension-stud is preferably of tubular form to receive the tension-releasing pin 35 whose outer end is adapted to bear upon the cross-bar 12 of the washer 11, the opposite end being engaged by suitable means for relieving the pressure of the tension-spring when required.

50 While the present improvement is shown and described herein in the preferred form and arrangement of its component parts, it is obvious that these may be modified to a certain extent without departure from the invention. It is also obvious that the device is capable of application to portions of the machine other than the face-plate without substantial alteration and such application is within the scope of the invention.

55 Having thus set forth the nature of the invention, what I claim herein is:—

1. In a sewing machine, in combination, a support, a bushing secured to said support and provided with a bearing aperture, a cy-
60 lindrical casing secured to said support inde-

pendently of said bushing and concentrically with the bearing aperture of the latter, a shouldered stop-member concentric with and fitted to one of the cylindrical faces of said casing, a stud fitted to the bearing aperture 70 of said bushing, a thread-controller spring surrounding and having one end connected to said stud and provided at the other end with a lateral thread-arm resting against the shoulder of said stop-member, a set-screw 75 accessible through said casing and entering the bushing for securing said stud adjustably within the latter, and a clamp-screw for securing said stop-member adjustably to said casing. 80

2. In a sewing machine, in combination, a support, a bushing secured to said support and provided with a bearing aperture, a cylindrical casing secured to said support independently of said bushing and concentrically with the bearing aperture of the latter and formed at one side thereof with a loop 85 affording an adjacent integral socket, a shouldered stop-member concentric with and fitted to one of the cylindrical faces of said casing, a stud fitted to the bearing aperture of said bushing, a thread-controller spring surrounding and having one end connected to said stud and provided at the other end with a lateral thread-arm resting against the 90 shoulder of said stop-member, a set-screw accessible through said casing and entering the bushing for securing said stud adjustably within the latter, a clamp-screw for securing said stop-member adjustably to said 95 casing, and a rigid thread-guard pin secured within said socket of the casing by a fusible metal bond. 100

3. In a sewing machine, in combination, a support, a bushing secured to said support and provided with a bearing aperture, a cylindrical sheet-metal casing provided at one end with prongs entering and riveted within apertures of said support concentrically with the bearing aperture of said bushing, a shouldered stop-member concentric with and fitted to one of the cylindrical faces of said casing, a stud fitted to the bearing aperture of said bushing, a thread-controller spring surrounding and having one end connected to said stud and provided at the other end with a lateral thread-arm resting against the shoulder of said stop-member, a set-screw accessible through said casing and entering the bushing for securing said stud 110 adjustably within the latter, and a clamp-screw for securing said stop-member adjustably to said casing. 115

4. In a sewing machine, in combination, a sheet-metal face-plate formed with a circular series of apertures and with a central aperture, a bushing formed with a bearing aperture and with a stud entering the central aperture of said face-plate in which it is secured, a cylindrical sheet-metal casing pro- 120 125 130

vided at one end with prongs entering the apertures of said circular series in the face-plate in which they are secured, a tubular shouldered stop-member concentric with and fitted within said casing, means for securing it adjustably within said casing, a stud fitted within the bearing aperture of said bushing, means for securing it adjustably therein, and a thread-controller spring surrounding 10 and having one end connected to said last-named stud and provided at the other end with a lateral thread-arm resting against the shoulder of said stop-member.

5. In a sewing machine slack-thread controller, the combination with a stud and a controller-spring having at one end a connection therewith and at the other end a lateral thread-arm, of a cylindrical sheet-metal casing inclosing the spring, a fixed support to 15 which said casing is secured, a bushing secured within said casing to said support and provided with an axial bearing aperture for said stud, a set-screw applied to said bushing for securing the stud adjustably in its bearing aperture, a tubular stop-member fitted within said casing and surrounding 20 said bushing and provided with a shoulder for engagement with the lateral thread-arm of said spring, and a clamp-screw for securing 25 said stop-member in circularly adjustable position upon said casing.

6. In a sewing machine slack-thread con-

troller, the combination with a stud and a controller-spring having at one end a connection therewith and at the other end a lateral thread-arm, of a cylindrical sheet-metal casing inclosing the spring, a fixed support to 35 which said casing is secured, a bushing secured within said casing to said support and provided with an axial bearing aperture for 40 said stud, a set-screw applied to said bushing for securing the said stud adjustably in its bearing aperture, a sheet-metal stop-member fitted to a cylindrical wall of said casing for engagement with the lateral 45 thread-arm of said spring, and a clamp-screw for securing said stop-member in circularly adjustable position upon said casing.

7. In a slack-thread controller, a casing, a support therefor, a shouldered stop-member mounted within and adjustably connected to said casing, a centrally apertured bushing secured to said support, a stud mounted for circular adjustment within said bushing, 50 a thread-controller spring secured at one end 55 to said stud and having a laterally extending arm for engaging the thread at its other end, and means for clamping said stud in circularly adjusted position whereby the tension of said thread-controller spring may be varied to suit the requirements of the work.

In testimony whereof, I have signed my name to this specification.

JOHN D. KARLE.
